UNITED STATES PATENT OFFICE.

LOUIS SAMETZ AND ADOLPH R. SAMETZ, OF NEW YORK, N. Y.

DESIGN FOR A CHILD'S RATTLE.

46,969.

Specification for Design.

Patented Feb. 16, 1915.

Application filed November 10, 1914. Serial No. 871,409. Term of patent 3½ years.

To all whom it may concern:

Be it known that we, LOUIS SAMETZ and ADOLPH R. SAMETZ, citizens of the United States, residing in the city of New York, borough of Brooklyn, county of Kings, and State of New York, have invented a new, original, and ornamental Design for a Child's Rattle, of which the following is a specification, reference being had to the accompanying drawings, forming part thereof.

The figure illustrates a child's rattle, showing our new design.

We claim—

The ornamental design for a child's rattle as shown.

LOUIS SAMETZ.
ADOLPH R. SAMETZ.
